ATTORNEY

UNITED STATES PATENT OFFICE

CARMELO ADORNETTO, OF NEW YORK, N. Y.

SANDPAPER HOLDER

Application filed June 4, 1932. Serial No. 615,296.

This invention relates to sandpaper or emery cloth holders and has for one of its objects the provision of a device of this character provided with a yieldable resilient core 5 over which a sheet of sandpaper or emery cloth is suitably held.

Another object of the invention is to provide means for securely holding the abrasive sheet in place as well as means for preliminarily holding the said sheet in place before the final holding means is applied thereto.

Another object is to produce a device of the character described in which the maximum simplicity of construction and operation is secured.

Other objects and advantages will appear as the nature of the improvements is better understood, the invention consisting substantially in the novel arrangement and co-relation of parts herein fully described, and illustrated in the accompanying drawing, wherein similar reference characters are used to describe corresponding parts throughout the several views, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an illustrative, rather than a restrictive standpoint.

The inventive idea involved is capable of receiving a variety of mechanical expressions, one of which, for the purpose of illustration, is shown in the accompanying drawing, in which.

Figure 1 is a vertical sectional view partly in elevation of my improved holder.

Figure 2 is a perspective view of the abrasive sheet support.

Figure 3 is a horizontal sectional view taken on line 3—3 Figure 1 and

Figure 4 is a detail view of one of the half rings forming the preliminary holding means.

Referring now to the drawing in detail 5 indicates a support preferably made of metal. The said support 5 comprises a thread-

ed disc portion 6 having a lower boss 7, through which boss and disc portion there is provided a central bore 8 adapted to receive the reduced end 9 of a shaft 10. The said support is secured to the reduced shaft 55 end 9 by means of a set screw 11.

The said support 5 is further provided with an upper boss 15 having a central bore 16 concentric with the bore 8 but somewhat larger in diameter than the diameter of the said bore 8. A pair of peripheral grooves 17 and 18 located at or near the bottom of the boss 15 together with a pair of substantial half rings 19 form means for temporarily securing a sheet of sand paper 20 or the like about the periphery of the boss 15. A central core 21 made of felt, sponge, rubber or the like and having a reduced portion 22 which fits into the bore 16 forms a resilient buffer and prevents the marring of any surface which is being abraded. It will of course be understood that the entire device is rotated with the shaft 10 extending from a suitable machine not shown.

To more permanently secure the abrasive sheet 20 about the support 5, there is provided a nut 25 which has at the top thereof an inwardly extending flange 26 having a central opening or bore 27. When the said nut 25 is screwed down in place the flange 26 clamps the outwardly extending flange 28 of the abrasive sheet against the top surface of the disc 6, and the metal defining the opening 27 in the flange 26 prevents accidental displacement of the half rings 19, thus providing positive means for securing the said abrasive sheet in place, the said means being readily removable when it is desired to replace a new sheet for one that has been worn out.

To assemble the device, the core 21 is first inserted into the opening 16, then the abrasive sheet is temporarily secured to the holder by springing the half rings 19 in place, and then the nut is screwed into place.

It will be seen that by temporarily holding the sheet 20 in place by means of the half rings, the final clamping of the said sheet by the nut 25 will be greatly facilitated.

It will also be understood that the said

half rings form auxiliary holding means which together with the nut 25 provide means for securely maintaining the abrasive sheet in place until removed.

5 From the foregoing, it will be seen that I have provided simple yet efficient means for holding an abrasive sheet about its support and one that will greatly facilitate the handling of the said sheet when being replaced.

10 I desire it understood that wherever in the claims I use the terms sand paper, emery cloth or abrasive sheet, any sheet of flexible material such as fabric or the like is to be included.

15 Having described my invention what I claim as new and desire to secure by Letters Patent is:

1. A holder for a sheet of sand paper, comprising a support having a peripheral groove, 20 a substantial half ring adapted to be snapped into the said groove for temporarily holding the sheet in place, and means for clamping the sheet against the support and maintaining the half ring in place.

25 2. A holder for a sheet of sandpaper, comprising a cylindrical support, an annular groove in the periphery thereof, an enlarged disc-like portion below the said groove, a substantial half ring adapted to snap into 30 the said groove for temporarily holding the sheet in place, and means for clamping the sandpaper against the enlarged disc portion and maintaining the ring in place.

3. A holder for a sheet of abrasive material, comprising a cylindrical support, a pair 35 of annular grooves in the periphery thereof, an enlarged disc-like portion below the said grooves and provided with an external thread, a pair of substantial half rings adapted to snap into the said grooves for holding 40 the said sheet about the support, and a nut on the disc portion to clamp the bottom of the sheet against the top surface of the said disc portion and maintain the half rings in 45 place.

4. A sandpaper holder comprising a disc-like member provided with threads on its periphery, a reduced cylindrical portion extending from the said disc member and provided 50 with an annular peripheral groove, a substantial half ring fitting into the said groove for maintaining the sandpaper about the periphery of reduced cylindrical portion, and a nut to clamp the sandpaper against one 55 surface of the disc-like member.

5. A holder for a sheet of sandpaper, comprising a cylindrical hub provided with a central longitudinal bore and an annular groove in the periphery thereof, a resilient 60 buffer in the said bore, the said hub and buffer forming a support for the sandpaper, an enlarged disc-like portion below the said annular groove, a substantial half ring fitting into the said groove for maintaining the 65 sandpaper about the support, and a nut to

clamp the lower edge of the sandpaper against the said disc-like portion.

In testimony whereof I have hereunto affixed my signature.

CARMELO ADORNETTO.
